UNITED STATES PATENT OFFICE.

ALLEN W. RUDY, OF DALTON, OHIO.

PADLOCK PROTECTOR.

Application filed August 3, 1921. Serial No. 489,440.

To all whom it may concern:

Be it known that I, ALLEN W. RUDY, a citizen of the United States of America, residing at Dalton, in the county of Wayne 5 and State of Ohio, have invented new and useful Improvements in Padlock Protectors, of which the following is a specification.

The object of the invention is to provide a simple and efficient and at the same time 10 inexpensive means for protecting a padlock from injury due to surreptitious or unauthorized efforts to open or break the same and also designed as a means for protecting the same from weather conditions, the design 15 of the protecting device being such as to permit of its application to padlocks of different sizes and constructions; and with this object in view the invention consists in a construction and combination of parts of 20 which a preferred embodiment is shown in the accompanying drawings, wherein:—

Figure 1 is a view of a padlock cover or protector embodying the invention applied in the operative position to and enclosing or 25 housing the padlock.

Figure 2 is a central vertical sectional view of the same.

Figure 3 is a sectional view similar to Figure 2 but taken in a plane at right angles 30 thereto.

Figure 4 is a transverse section on the plane indicated by the line 4—4 of Figure 2.

The cover or protector 10 is of substantially bell or dome shape, of a size adapted 35 to readily receive and house the padlock 11 and provided at its closed or arched end with a slot 12 adapted to receive and fit over the staple 13 which is engaged by the hasp 14, said staple extending through the 40 slot for a distance sufficient to enable the shackle 15 of the padlock to be engaged therewith.

The larger or base end of the protector is open to give access to the padlock housed 45 therein, but while the protector is preferably made of sheet metal, as a means of minimizing the cost thereof, it is preferably reinforced at its edge by a returned lap or bead 16 and at its sides by the spaced ribs 50 17 preferably disposed longitudinally of the

hood or in radial relation with the end slot 12.

Also openings 18 may be formed in the housing to permit of the passage of keys to give access to the key holes of the padlock. 55

While the housing, particularly when constructed of sheet metal, and it is preferred to construct the same of a pliable metal so as to bend rather than break, may be distorted by any efforts directed to the unauthorized or forcible opening of the lock or the breakage thereof, the lock casing will be protected from blows which would tend to injure the same, and the engagement of the housing with the staple prevents the use of 60 a lever or means of prying the staple or shackle or of inserting a lever through the shackle and between the same and the end of the padlock casing in an effort to strain 65 the shackle out of engagement with the casing. 70

Having described the invention, what is claimed as new and useful is:—

1. A padlock protector consisting of a domed or bell shaped housing for receiving 75 the padlock and provided at its closed end with means for engaging the staple with which the shackle of the padlock is engaged.

2. A padlock protector consisting of a domed or bell shaped housing having a slot 80 through which the staple engaged by the padlock shackle may be extended and provided with key hole openings and reinforcing means.

3. A padlock protector consisting of a 85 domed or bell shaped housing of pliable material provided with means for engaging a staple with which the padlock shackle is engaged and having an open base end.

4. A padlock protector consisting of a 90 domed or bell shaped housing of pliable material provided with means for engaging a staple with which the padlock shackle is engaged and having an open base end, the walls of the housing being provided with reinforcing ribs. 95

In testimony whereof he affixes his signature.

ALLEN W. RUDY.
